Gustav Diezemann

Conrad Augusto Dietrich
his ATTORNEY

UNITED STATES PATENT OFFICE.

GUSTAV DIEZEMANN, OF WEST HOBOKEN, NEW JERSEY.

SUSPENSION DEVICE FOR VEHICLES.

No. 840,049.

Specification of Letters Patent.

Patented Jan. 1, 1907.

Application filed April 3, 1905. Serial No. 253,426.

To all whom it may concern:

Be it known that I, GUSTAV DIEZEMANN, of West Hoboken, Hudson county, in the State of New Jersey, have invented certain new and useful Improvements in Suspension Devices for Vehicles, of which the following is a full, clear, and exact specification.

My invention relates to improvements in vehicles; and the same has for its object more particularly to provide a simple, efficient, and thoroughly reliable apparatus which may be easily applied to a vehicle intermediate its body portion and springs and so regulated in relation to the weight of the vehicle in order that the shock produced when the wheels encounter an obstruction or depression in the road and the consequent rebounding of the parts to their normal position will be entirely overcome, the action of the car over the road rendered smooth and free from all sudden jolt or undue vibration, and, finally, the tractive power of the wheel and the speed of the car materially increased.

To the attainment of these ends my invention consists in the novel details of construction and in the combination, connection, and arrangement of parts hereinafter more fully described, and then pointed out in the claims.

In the accompanying drawings, wherein like numerals of reference indicate like parts, Figure 1 is a side view of a portion of a vehicle-body and a spring with a suspension device constructed according to and embodying my invention applied thereto. Fig. 2 is an enlarged detail side view of the suspension device, showing the same attached to the body and spring; and Fig. 3 is a section taken on the line 3-3 of Fig. 2.

In said drawings, 10 designates the apparatus, comprising a support or plate 11, having an angular projection 12, extending upwardly therefrom at a point near its center, whereby the apparatus may be secured to the frame of the vehicle.

13 13' denote hollow integral cylindrical casings or barrels, whose open ends are provided upon their inner surfaces with screw-threads and their closed opposing ends provided with centrally-located apertures 14.

15 denotes a shaft extending through the apertures 14 in the ends of the casings or barrels 13 13' and having its end located within the barrel 13', provided with an integral flat head 16, corresponding in diameter substantially with that of the interior of the barrel 13', while the opposite end of said

shaft 15 is provided with a transverse rectangular slot 17, and 18 denotes a removable head having a central opening 19 therein, corresponding in diameter with that of the shaft 15, and a pin 20, extending through said removable head and the opening 19 therein and adapted to be received by the slot 17 when said removable head is adjusted in position upon the end of said shaft 15. 65

21 21 denote caps provided upon their edges with screw-threads adapted to engage those upon the inner surfaces of the barrels 13 13', and 22 22 circular recesses provided in the outer surfaces of said caps 21 21, adapted to receive the ends of a spanner or other instrument, whereby said caps 21 21 may be secured and adjusted in the ends of said barrels. 70

23 23 denote annular packings, preferably made of hard fiber, which are disposed upon the shaft 15 intermediate the heads 16 18 and the closed ends of the barrels 13 13', and 24 24 denote flat circular disks composed of the same material as the annular packings 23 23 and interposed between the outer surfaces of the heads 16 18 and the inner surfaces of the caps 21 21. 80

In order to prevent the rotation of the annular packings, the same are provided in their edges with recesses 25 and screws or pins 26, which extend through the barrels 13 13' into said recesses, and thus hold the same duly in position. 85

27 27 denote oil-holes through which a suitable lubricant may be introduced into the barrels 13 13'. 90

28 denotes an arm, which is keyed to the shaft 15 intermediate the barrels 13 13' by means of a pin 29, and the outer end of said arm pivotally connected to one end of a link 30, and 31 denotes a bearing consisting of a plate 32, having a lateral projection provided with upwardly-projecting ears or lugs 33, intermediate of which is pivotally secured the lower end of the link 30. The said bearing 100 31 is secured to the upper surface of the spring 34 near the vehicle-axle by U-bolts or straps 35. 95

It is to be noted that in my improved construction I provide a plurality of friction-bearings, which may be increased by incorporating into the structure any number of removable heads, such as 18 47, and the frictional engagement of the fixed and removable heads so regulated as to effect the requisite or desired degree of retardation by turning the caps 21 21 more or less, and thereby 110

increasing or diminishing, as the case may be, the degree of frictional contact between the fixed and removable heads and the fiber packings and the surfaces of the barrels contacting therewith.

5 It is to be noted that my apparatus is applicable to wheeled vehicles of all descriptions, and that by its application thereto the rising and falling of the body upon the axles or running-gear and the consequent compression and expansion of the springs will be so retarded as to render the action of the vehicle smooth and free from all undue jolting or vibration.

15 Without limiting myself to the details of construction, which may be varied within the scope of the invention, what I claim, and desire to secure by Letters Patent, is—

1. A suspension device for vehicles comprising a closed casing adapted for securement to a vehicle, a shaft revolubly supported in said casing, a head arranged within said casing, packings arranged at right angles to said shaft and contacting with said head for retarding the rotation of said shaft, and mechanism interposed between said shaft and the vehicle-axle, substantially as specified.

2. A suspension device for vehicles, comprising a closed casing adapted for securement to a vehicle, a shaft revolubly mounted in said casing, heads arranged upon said shaft and revoluble therewith, means adapted to coöperate with said heads to retard the rotation of said shaft, and mechanism interposed between said shaft and the vehicle-axle, substantially as specified.

3. A suspension device for vehicles comprising a closed casing adapted for securement to a vehicle, a shaft revolubly mounted in said casing, heads arranged upon said shaft and revoluble therewith, means adapted to coöperate with said heads to retard the rotation of said shaft, means for maintaining the retarding means in operative relation, and mechanism interposed between said shaft and the vehicle-axle, substantially as specified.

4. A suspension device for vehicles comprising a closed casing adapted for securement to a vehicle, a shaft revolubly mounted in said casing, heads arranged upon said shaft and revoluble therewith, friction material arranged in contact with said heads and adapted to coöperate therewith to retard the rotation of said shaft, and mechanism interposed between said shaft and the vehicle-axle, substantially as specified.

5. A suspension device for vehicles, comprising a closed casing adapted for securement to a vehicle, a shaft revolubly mounted in said casing, heads arranged upon said shaft and revoluble therewith, friction material interposed between said heads and the ends of the casing and adapted to coöperate

with said heads to retard the rotation of said shaft, and mechanism interposed between said shaft and the vehicle-axle, substantially as specified.

6. A suspension device for vehicles comprising a closed casing adapted for securement to a vehicle, a shaft revolubly mounted in said casing, heads arranged upon said shaft and revoluble therewith, packings arranged independently of said shaft intermediate said heads and the ends of said casing adapted to coöperate with the heads upon the shaft to retard the rotation of said shaft, means for maintaining the adjusted relation of said retarding means, and mechanism interposed between said shaft and the vehicle-axle, substantially as specified.

7. A suspension device for vehicles, comprising a closed casing adapted for securement to a vehicle, a shaft revolubly mounted in said casing, means arranged upon said shaft and adapted to rotate therewith, a part of said means being fixed thereon and a part removable, means arranged in contact with said fixed and removable means, and adapted to coöperate therewith to retard the rotation of said shaft, and mechanism interposed between said shaft and the vehicle-axle, substantially as specified.

8. A suspension device for vehicles comprising a closed casing adapted for securement to a vehicle, a shaft revolubly mounted in said casing, means arranged upon said shaft and adapted to rotate therewith, a part of said means being fixed thereon and a part removable, means arranged in contact with said fixed and removable means and adapted to coöperate therewith to retard the rotation of said shaft, means adjustably arranged in said casing for sealing the same, and maintaining said retarding means in operative relation, and mechanism interposed between said shaft and the vehicle-axle, substantially as specified.

9. A suspension device for vehicles comprising a closed casing adapted for securement to a vehicle, a shaft revolubly mounted in said casing and arranged partly within and partly without the same, means therefor arranged upon said shaft and adapted to rotate therewith, retarding means in frictional engagement with the means arranged upon said shaft and coöperating therewith to impede the free movement of said shaft, and mechanism interposed between the portion of the shaft without said casing and the vehicle-axle, substantially as specified.

10. A suspension device for vehicles comprising a closed casing adapted for securement to a vehicle, a shaft revolubly mounted in said casing and arranged partly within and partly without said casing, a plurality of heads arranged upon said shaft and adapted to rotate therewith, retarding means in frictional engagement with said heads to impede

the free movement of said shaft, means for regulating the engagement of said retarding means with said heads, and mechanism interposed between the outer portion of said shaft and the axle of the vehicle, substantially as specified.

11. A suspension device for vehicles comprising a casing adapted for securement to a vehicle, a shaft revolvably mounted in said casing and arranged partly within and partly without the same, a plurality of heads arranged upon said shaft and adapted to rotate therewith, packings disposed in said casing in contact with said heads, means for maintaining said packings in contact with and bearing against said heads to impede the free movement of said shaft, and mechanism interposed between the outer portion of said shaft and the vehicle-axle, substantially as specified.

12. A suspension device for vehicles comprising a casing, means for securing the same to a vehicle, a shaft arranged partly within and partly without said casing, a plurality of heads arranged upon said shaft and adapted to rotate therewith a part of said heads being fixed thereon and a part thereof removable, packings disposed in said casing in contact with said heads, means for closing said casing and maintaining said packings in contact with and bearing against said heads to impede the free movement of said shaft, and mechanism interposed between the outer portion of said shaft and the vehicle-axle, substantially as specified.

13. A suspension device for vehicles comprising a casing, a support therefor, adapted for securement to a vehicle, a shaft arranged partly within and partly without said casing, heads arranged within said casing upon said shaft, packings disposed within said casing in contact with said heads, means for holding said packings against rotary movement, means for closing said casing and maintaining said packings in contact with and bearing against said heads, an arm secured at one end to the outer portion of said shaft, and a link connected to the other end of said arm,

and the vehicle-axle, substantially as specified.

14. A suspension device for vehicles comprising a casing consisting of two separated cylindrical barrels united by a support adapted for securement to a vehicle, a shaft supported at its ends in said cylindrical barrels, heads arranged upon the ends of said shaft located within said cylindrical barrels, packings disposed within said cylindrical barrels in contact with said heads, caps for closing the ends of said cylindrical barrels adapted to maintain said packings in contact with and bearing against said heads, mechanism interposed between the exposed portion of said shaft and the vehicle-axle, substantially as specified.

15. A suspension device for vehicles comprising a casing consisting of two separated cylindrical barrels united by a support adapted for securement to a vehicle, a shaft supported at its ends within said casing having a fixed head at one end located in one of said cylindrical barrels, and a removable head at its other end located in the other of said cylindrical barrels, means arranged upon the end of said shaft adapted to engage and hold said removable head, annular packings disposed upon said shaft intermediate the heads thereon and the ends of said cylindrical barrels, disk packings disposed upon the outer surfaces of said heads, screw-caps for closing the open ends of said cylindrical barrels adapted to bear against said disk packings, an arm having one end keyed to said shaft intermediate the cylindrical barrels, a bearing secured to the vehicle-spring adjacent to the vehicle-axle, and a link pivotally connected to said bearing and the outer end of the arm aforesaid, substantially as specified.

Signed at the city of New York, in the county and State of New York, this 31st day of March, 1905.

GUSTAV DIEZEMANN.
